UNITED STATES PATENT OFFICE.

OLIVER P. JAQUES, OF WARSAW, INDIANA.

ICE-TOOL.

SPECIFICATION forming part of Letters Patent No. 425,325, dated April 8, 1890.

Application filed August 3, 1889. Serial No. 319,703. (No model.)

To all whom it may concern:

Be it known that I, OLIVER P. JAQUES, of Warsaw, in the county of Kosciusko and State of Indiana, have invented a new and useful 5 Ice-Tool for Cutting Between the Cakes of Ice in the Ice-House; and I do hereby declare that the following is a full, clear, and exact description thereof, reference being had to the accompanying drawings, in which—

10 Figure 1 is a side elevation of my improved ice-tool, and Fig. 2 is a transverse section taken on the section line drawn through Fig. 1.

The nature of my invention consists of an 15 ice-tool, made as herein described and shown, that may be worked between the cakes of ice in the ice-house for the purpose of separating them with the least possible waste of ice and accumulation of slush, cutting a smooth and regular channel reaching to the remotest 20 depths of square corners and leaving the cakes of ice in a more perfectly rectangular form than by any other means heretofore used.

The tool is constructed from an iron or a 25 steel plate one-fourth ($\frac{1}{4}$) of an inch in thickness, about four ($\frac{1}{4}$) inches in width, and in length sufficient to form three or more teeth about three inches long, as shown, and a shank of convenient length and size to be fitted into a wooden handle. If an iron plate is used, the 30 teeth are pointed with steel. The teeth are formed by cutting out openings in the plate, as shown at *d* and *c*, and swaged down so as to be about five-eighths of an inch in thickness at the point, which is brought to a sharp 35 chisel-shaped edge. In the formation of the

openings, as shown at *d* and *c*, the parts from 1 to 2 and from 3 to 4 are brought to a central tapering cutting-edge, so that in use the tool is readily relieved from accumulation of slush ice.

The points or cutting portions of the teeth B and C are made to project or extend a trifle beyond the line of the tooth A, so that when the tool is used at any convenient angle the teeth B and C do the principal portion of the 45 cutting, and when used in a vertical position the tooth A, then acting as a chisel, cuts out the square corners to the very bottom of the 50 cakes of ice.

Having thus described my invention, what 50 I claim as new, and desire to secure by Letters Patent, is—

1. The ice-tool having the series of teeth formed with broad base or surface portions having wide chisel-edge-shaped points and 55 with an upper forward central tapering cutting-edge, substantially as set forth.

2. The ice-tool having the series of teeth of approximately plow-shovel shape in side elevation, formed with broad base or surface portions, having wide chisel-edge-shaped points and with upper forward central tapering cutting-edge, the points of each succeeding tooth being below the preceding tooth, all in one 60 piece, substantially as set forth.

OLIVER P. JAQUES.
